UNITED STATES PATENT OFFICE.

DONALD K. CHAMPAIGN, OF ITHACA, NEW YORK.

INTAKE-MANIFOLD.

1,342,159.

Specification of Letters Patent.

Patented June 1, 1920.

Application filed October 30, 1918. Serial No. 260,285.

To all whom it may concern:

Be it known that I, DONALD K. CHAMPAIGN, a citizen of the United States, residing at Ithaca, Tompkins county, and State of New York, have invented and discovered certain new and useful Improvements in Intake-Manifolds, of which the following is a specification.

My said invention relates to a multi-passage inlet manifold for internal combustion engines and consists in the combinations and arrangements of elements hereinafter described and particularly set forth in the accompanying claims.

15 The invention has for its purpose to provide a manifold having separate passage-ways whereby a portion of the fuel charge is heated by the exhaust gases from the engine.

20 The theory advanced as the basis of this invention is that it is advantageous to heat the mixture from the carburetor before allowing it to enter the cylinders of motor cars when starting the motor or in very cold weather, also with a small passage in the manifold the velocity of the gas is high enough to give good operation at low speeds and that at high speeds the cross-section of the manifold is enlarged to a sufficient size 25 so that there will not be a choking effect with the drop in volumetric efficiency accompanying any choking of the inlet passage.

Referring to the accompanying drawings, 30 wherein like reference characters indicate corresponding parts.

Figure 1 is an elevation showing the application of the manifold to a multi-cylinder engine.

40 Fig. 2, a transverse sectional view thereof taken on the line 2--2.

Fig. 3, a horizontal sectional view taken on the line 3--3 of Fig. 1, and

45 Figs. 4 and 5 are diagrammatic illustrations showing the relative efficiencies of the present system I now propose.

In said drawings the portions marked 6 represent an ordinary multi-cylinder internal combustion engine equipped with the 50 usual intake and exhaust valves, 7 and 8 respectively, and having any suitable form of carburetor 9 as shown.

The multi-passage intake manifold consists of a suitable hollow metal structure 55 forming a central part 10 that has com-

municating connection with the carburetor 9, and branches 11 communicating with the respective intakes of the engine cylinders. A partitioning wall 12 divides the intake manifold into chambers or passage-ways 13 and 14 having relatively different volumetric capacities, and the former is normally relied upon for transferring the fuel from the carburetor to the engine for all speeds up to approximately fifteen miles 60 per hour. To this end the smaller fuel passage-way 13 is partially surrounded by the casing or wall 15 forming the chamber 16 that receives the exhaust gases from the engine cylinders, and a discharge pipe 17 65 leads to a muffler or the atmosphere direct.

A valve 20 having operating means 21 connected thereto is interposed in the pipe leading from the exhaust manifold of the engine to the casing 15 for the purpose of 70 shutting off the exhaust gases when the engine has properly warmed up.

It has been found to be true with the present day motor cars that the volumetric efficiency of the motor falls off when the 80 speed of travel goes beyond approximately fifteen miles per hour as indicated by the curve in Fig. 4 and this falling off is due to the fact that a manifold that has a sufficient volumetric capacity at low speed is insufficient for high speed, thereby causing an incomplete charge at high speed. It has also been found true that an engine running at slow speed and using a cold charge has not the efficiency of one in which a hot 90 charge is admitted, whereas the engine in almost any motor car when traveling at more than fifteen miles per hour has sufficient suction to successfully use a cold charge. 95

By this invention I obviate this defect by providing the additional fuel passage-way 14 constructed as an integral part of the used manifold to come into use when such a speed is reached that passage-way 13 is 100 too small. Both passage-ways 13 and 14 are controlled by a sliding valve 18 and having actuating means 19 connected thereto, and running to a point within reach of the operator. This valve forms the throttle 105 valve for the engine and is designed to open the small port 13 first. By this provision the auxiliary manifold 14 may be opened to take variable charges of fuel from the carburetor and without subjecting the same to 110

any heat by the exhaust gases inasmuch as it has been ascertained that by this method the volumetric efficiency does not depreciate with the increased rate of travel.

5. Having thus fully described my said invention, what I claim as new and desire to secure by Letters Patent, is:

1. An intake manifold embodying a hot conduit and a cold conduit and means to 10 open communication, first through the hot conduit and progressively through the cold conduit.

2. An intake manifold embodying a hot conduit and a larger cold conduit and means 15 to open communication first through the hot

conduit and progressively through the cold conduit.

3. An intake manifold embodying a hot conduit and a cold conduit differing in carrying capacity and means to open communication first through the hot conduit and progressively through the cold conduit. 20

In witness whereof I have hereunto set my hand and seal at Washington, District of Columbia, this twenty-ninth day of October, A. D. nineteen hundred and eighteen. 25

DONALD K. CHAMPAIGN. [L. S.]

Witnesses:

E. W. BRADFORD,
B. C. SPENCER.
